UNITED STATES PATENT OFFICE.

HORACE B. GALE, OF NATICK, AND FRED M. DEWING, OF BOSTON, MASSACHUSETTS, ASSIGNORS TO SUBMARINE SIGNAL COMPANY, OF WATERVILLE, MAINE, A CORPORATION OF MAINE.

MEANS FOR PRODUCING SOUND-VIBRATIONS IN WATER.

No. 813,964.

Specification of Letters Patent.

Patented Feb. 27, 1906.

Application filed August 21, 1903. Serial No. 170,279.

To all whom it may concern

Be it known that we, HORACE B. GALE, of Natick, in the county of Middlesex, and FRED M. DEWING, of Boston, in the county of Suffolk, State of Massachusetts, citizens of the United States, have invented a new and useful Improvement in Means for Producing Sound-Vibrations in Water, of which the following is a full, clear, and exact description, reference 10 being had to the accompanying drawings, forming a part of this specification, in explaining its nature.

The invention relates to a means for producing sound-vibrations in water, whereby 15 the sound-vibrations may be imparted to the water and be carried thereby as a transitory medium, and which means, moreover, is so adapted as to be actuated or influenced by the movement of the water or by hand or 20 other mechanical expedient.

The object of our invention is to produce a 25 submarine sound signaling apparatus which shall have effective sound-producing capacity, which may be conveniently suspended 30 in the water or otherwise manipulated, and which is so constructed as to be easily 35 acted upon or operated by the motion of the boat or other floating structure from which the apparatus is suspended.

30 The invention is illustrated by the accompanying drawings, forming a part of this specification, wherein—

Figures 1 and 2 show in elevation contrasting 35 views of the sound-producing apparatus as suspended from a boat. Fig. 3 is a cross vertical section with a portion of the sound-producing apparatus shown in side elevation. Fig. 4 shows the same, but with a change in 40 the disposition of the operative parts to which reference will hereinafter be made. Fig. 5 shows, essentially, an end elevation of a portion of the sound-producing apparatus. Fig. 6 shows a detail of construction to which 45 reference will hereinafter be made.

Referring to the drawings, A indicates the 50 outer shell or case of the sound-producing device, in which is contained the sound-producing mechanism. The outer shell or case is shown suspended from a floating structure, 55 as a boat B, the means of suspension comprising two cords or equivalent means C C', the cord C being fixed to the top of said shell or case, either with a direct or through some

auxiliary connection, and the cord C' assisting in the suspension of the shell or case and 55 connecting with the mechanism on the inside thereof, as will hereinafter be explained. The cords at their upper ends are secured to the side of the boat, ranged fore and aft at the points 1 and 2, respectively, (see Fig. 1,) or 60 upon opposite sides thereof at the respective points 3 and 4, as may be seen in Fig. 2, this in order that the pitching or rocking motion of the boat imparted to it by the natural movement of the water or otherwise obtained 65 may be most effectively utilized.

The exterior shell or case A is made preferably of metal and of approximately a cylindrical formation. Upon the inside thereof, projecting inwardly, is an annular ring or 70 bow D, which may be of an integral or auxiliary formation with that of the case. In the drawings it is shown formed integrally with the case. By forming the shell or case with the ring thus disposed it sounds, when struck, 75 with a relatively high pitch, which has been found to be most effective in submarine signaling. Moreover, formed as it is the shell or case can be made relatively light in structure, which especially fits it for suspension in 80 the water from a small boat or to be otherwise manipulated. On the inside the shell or case gives a large chamber for the striking mechanism, while on its outside surface it presents a smooth rounding exterior surface, 85 on which seaweed or other debris cannot easily lodge.

E represents a striker adapted to strike the ring D, so causing it to sound. The striker 90 E, as shown, is pivoted on the pin p, which passes through a slot s in the striker-arm and is held by a frame M, attached to the case A, which frame may, if desired, be formed integrally therewith. In this connection it is to be noted that the slot s, by which the 95 striker-arm is pivotally secured to pin p, has a somewhat elliptical formation, whereby the striker-arm has a slight degree of play upon said pin, this for purposes as will hereinafter be explained. It is also to be noted that the 100 frame M is extended up with a neck, as it were, through an opening formed in the top of the case, the case practically resting upon shoulders formed thereby, and through which extended neck passes the pin a, to which the 105 end of the cord C is secured by suitable link

connection. This is an arbitrary feature of construction, however, for the case itself may just as well be extended to receive the direct connection of the cord C. Secured to the upper end of the striker-arm and projecting laterally from either side thereof are the pins $p' p''$, respectively. Attached to these separate pins are the ends of respective springs F F'. The springs at their opposite ends are secured by suitable pin connections $p^3 p^4$ to the arm g of the rocker-lever G, which is pivoted at the point p^5 to the frame M. Pivoted at the point k to the arm g' of the said rocker-lever is a link H, carrying at its upper end one or more pulleys I, with a connecting-pin i' , and around which pulleys the cord C' is passed to where its end is secured to the shell or case A at the point c. The pulley or pulleys I are preferably supplemented by the pulley or pulleys J, around which the cord C' is also passed after being passed around the pulley I before its end is fixed. The pulleys J, it is to be noted, are arranged in the top of the shell or case A or in the neck of the frame M, which extends through the top of said case, and preferably by the same pivotal pin a by which the end of the cord C is secured thereto, as before explained. Carried by the arm g' of the said rocker-lever G and by the same connecting-pin which secures the link H is the latch L. It is to be noted by reference to the detail of construction shown in Fig. 6 that the said arm of the lever is made cleft at its end to receive said latch and also to form two stop-surfaces therefor, as it were, $g^2 g^3$, by contacting with which the latch has a certain defined radial swing, the surface g^2 defining the swing of the latch in one direction by the contact of its rear end against said surface (see Fig. 3) and the surface g^3 , if the occasion demands, defining the swing of the latch in the opposite direction, this by the contact of its side against said surface. The latch is over-weighted, so as to assume a normal position like that shown in the full lines on Fig. 3, with its rear end contacting with the stop-surface g^2 thereof, and the latch, moreover, is of such relative size that it will contact with the cam-surface T of the striker-arm, wherefore the striker-arm is thrown forward, causing not only a further extension of the springs, but also forcing the striker-arm into an operative position. When the parts have assumed a position substantially like that shown in Fig. 4, a slight further motion of the rocker-arm G carries the latch L beyond the end of the cam-surface T, with which it engages, and the striker-arm becomes released. The retraction of the springs F F' then throws the striker E down to its normal position, (shown in the dotted lines of Fig. 3,) and the momentum thus acquired by the striker carries it beyond this position to that shown in the full lines of Fig. 3, or to where its head contacts with the ring D, causing it to sound. This further movement of the striker, caused by the momentum just referred to, is made permissible by the extension of its slot s, whereby the arm of the striker has such freedom of movement relatively to its pivotal connection passing through the slot that the

drawn away from a normal contact with the ring D by reason of the fact that the upper end of the striker-arm is drawn by the springs against a stop N, which is attached to the inner side of the case A, so that the striker-arm fulcruming against the stop is drawn back upon its pivotal connection by reason of the extension of its slot s to where its head assumes the relative normal position aforesaid, this being commensurate with the amount of the slot's extension.

The operation of the sound-producing apparatus is as follows: With the cords C C' secured to the side of the boat fore and aft or to opposite sides thereof whatever pitching or rocking motion is imparted to the boat by the motion of the water results in the cords C C' being alternately slackened and tightened, so that the whole or part of the weight of the case A and inclosed parts will be transferred alternately from the cord C to the cord C', and vice versa. When the pendent weight of the apparatus comes upon the cord C, there will be no resultant influence exerted upon the parts constituting the striking mechanism by reason of the fact that the cord C is fixed to the case or to the frame extending therefrom, as before referred to; but when the cord C becomes slackened and the weight of the apparatus is transferred to the cord C' this becomes tightened, and consequently as it connects with the interior mechanism the resultant operation would be to draw up the pulleys I, carrying with them the link H, and so turning the rocker-lever G. The turning or drawing up of the rocker-lever causes the springs F F' to be somewhat extended by the drawing stress of the lever-arm g, and when the rocker-lever has been sufficiently drawn up or turned the latch L, carried by its arm g' and reinforced by its stop-surface g^2 , as before explained, is made to engage with the cam-surface T of the striker-arm, wherefore the striker-arm is thrown forward, causing not only a further extension of the springs, but also forcing the striker-arm into an operative position. When the parts have assumed a position substantially like that shown in Fig. 4, a slight further motion of the rocker-arm G carries the latch L beyond the end of the cam-surface T, with which it engages, and the striker-arm becomes released. The retraction of the springs F F' then throws the striker E down to its normal position, (shown in the dotted lines of Fig. 3,) and the momentum thus acquired by the striker carries it beyond this position to that shown in the full lines of Fig. 3, or to where its head contacts with the ring D, causing it to sound. This further movement of the striker, caused by the momentum just referred to, is made permissible by the extension of its slot s, whereby the arm of the striker has such freedom of movement relatively to its pivotal connection passing through the slot that the

head of the striker has contact with the ring; but after such contact, the upper end of the striker E then fulcruming against the stop N, the tension of the springs draws the striker 5 back so far as the extension of the slot s will allow or to the position substantially like that shown in the dotted lines of Fig. 3. When the cord C' is slackened by the weight of the apparatus being transferred to the cord 10 C and its drawing stress accordingly let go, then the further retraction of the springs F F' draws the rocker-lever back to its normal position, like that shown in Fig. 3. During the withdrawal of the rocker-lever the latch 15 L is carried by it and takes a position substantially like that shown in the dotted lines of Fig. 3 until it has passed the end of the cam-surface T of the striker-arm, when it gravitates to the normal position, (shown in 20 the full lines thereof,) ready for engagement with the said cam-surface of the striker-arm, when the parts are again actuated. Any displacement of the latch is prevented by the back stop-surface g', formed in the lever-arm 25 g', with which it may engage when occasion requires. It is obvious that the tension that can be applied to the cords C C' to properly operate the apparatus is limited by the weight of the suspended parts, and in order to use 30 springs sufficiently strong to deliver the desired blow on the ring D the cord C' is preferably passed around the pulleys I and J a sufficient number of times to multiply the force applied to the cord to the degree required to extend the springs.

We have described the bell more particularly as operated by the motion of the waves given to the boat; but it is evident that if the bell is hung by one cord—for example, C—40 the cord C' can be alternately drawn tight and slackened by hand to operate the bell.

We have shown the cord C' as continuing down and around the pulleys I and J. (See especially in Fig. 3.) It is evident that a 45 chain or other flexible connection may be substituted for the cord, either entire or for so much of the cord as passes around these pulleys.

The details of the striking mechanism may 50 be very greatly varied, and we do not limit our invention to the specific details of structure herein shown and described. The means shown, however, constitute the form in which we prefer to construct the apparatus, especially for suspension from small boats to be 55 operated either by the motion imparted to the boat by the waves or by hand or by any other mechanical expedient.

Having thus fully described our invention, 60 we claim and desire to secure by Letters Patent of the United States—

1. In an apparatus for producing sound-vibrations in water, the combination with 65 separate means of suspension of a sound-producing device hanging pendent therefrom,

the same comprising a resonant body, and means for sounding said resonant body by the transfer of the whole or part of the weight of said device from one suspending means to another.

2. In an apparatus for producing sound-vibrations in water, the combination with separate means of suspension of a sound-producing device hanging pendent therefrom, the same comprising a resonant body, a 75 striker therefor, and means whereby said striker may be operated by the transfer of the weight of said device from one suspending means to another.

3. In an apparatus for producing sound-vibrations in water, the combination with a floating structure and separate means of suspension attached at their upper ends at separate points thereto, of a sound-producing device from the lower ends of which means of 85 suspension said sound-producing device hangs pendent, the same comprising a submerged resonant body, a striker adapted to strike the same so as to produce sound, and means whereby said striker may be operated by the 90 transfer of the whole or a part of the weight of said device from one suspending means to another.

4. In an apparatus for producing sound-vibrations in water, the combination with a 95 floating structure and suspension-cords secured at their upper ends thereto of a sound-producing device from the lower ends of which cords said sound-producing device hangs pendent, the same comprising a sub- 100 merged resonant body, a striker therefor, and means adapted to be operated upon for actuating said striker, which means is submerged with said resonant body and is so connected with one of said suspension-cords as 105 to be operated upon thereby with the transfer of the weight of said device from one suspending-cord to the other.

5. In an apparatus for producing sound-vibrations in water, a bowl-shaped casing of 110 large internal diameter to contain a powerful striking mechanism, a powerful striking mechanism within the same, and a resonating section at mouth of said casing of appreciably less internal diameter than the internal diameter of the casing, whereby the apparatus while producing sound of high pitch by reason of its small resonating section is designed by reason of the large bowl-shaped casing to contain striking mechanism 115 of sufficient power for submarine signaling purposes.

6. In an apparatus for producing sound-vibrations in water, a bowl-shaped casing of 120 large internal diameter to contain a powerful striking mechanism, a powerful striking mechanism within the same, a striker actuated by said mechanism, means for operating the mechanism from without the casing, and a resonating section at the mouth of said 130

casing of appreciably less internal diameter than the internal diameter of the casing, whereby the apparatus while producing sound of high pitch by reason of its small resonating section, is designed by reason of the large bowl-shaped casing to contain striking mechanism of sufficient power for submarine signaling purposes.

7. In an apparatus for producing sound-vibrations in water, the combination with a floating structure and separate means of suspension attached at their upper ends at separate points thereto, of a sound-producing device from the lower ends of which means of suspension said sound-producing device hangs pendent, the same comprising a submerged resonant body, a striker adapted to strike the same so as to produce sound, means adapted to be operated upon by one of said means of suspension for raising said striker into a striking position, and an instantaneous release.

8. In an apparatus for producing sound-vibrations in water, the combination with a floating structure and separate means of suspension attached at their upper ends at separate points thereto, of a sound-producing device from the lower ends of which means of suspension said sound-producing device hangs pendent, the same comprising a submerged resonant body, a striker adapted to strike the same so as to produce sound, means connected to be operated upon by said means of suspension for actuating said striker, and a returning-spring for restoring said means to a normally operative position.

9. In an apparatus for producing sound-vibrations in water, the combination with a floating structure and two cords attached at their upper ends thereto of a sound-producing device from the lower end of which cords said sound-producing device hangs pendent, the same comprising a resonant body, a striker therefor, and means for receiving the draft exerted upon one of said cords by the weight of said sound-producing device or a portion thereof being transferred thereto from the other of said cords whereby the power thus obtained may be utilized to raise said striker to a striking position, means for effecting its instantaneous release, and means for maintaining the parts in a normal position to be operated upon by the draft aforesaid.

55 10. In an apparatus for producing sound-vibrations in water, the combination with a floating structure and two cords attached at their upper end at separate points thereto, of a sound-producing device from the lower end of which cords said sound-producing device hangs pendent, the same comprising a submerged resonant body, and an apparatus contained within the same for sounding said resonant body by the transfer of the weight 60 of said device from one cord to the other, said

apparatus consisting of a striker, a movable member adapted to be moved by the draft of one of the suspending-cords when the weight of the sound-producing device comes thereon and to impart its motion to the said 70 striker to raise the same to a striking position, where it may become automatically released.

11. In an apparatus for producing sound-vibrations in water, the combination with two suspending-cords of a sound-producing device hanging pendent from the lower ends thereof, the same comprising a resonant body, a striker contained within the same, a lever connected to actuate said striker by the 80 draft exerted by the weight of the said sound-producing device or a portion thereof being transferred from one of its suspending-cords to the other, and means for holding said lever in a normally operable position. 85

12. In an apparatus for producing sound-vibrations in water, the combination with two suspending-cords of a sound-producing device from the lower ends of which said sound-producing device hangs pendent, the 90 same comprising a resonant body, a striker carried by the same, a lever connected with said striker for actuating it, and means for receiving the draft exerted by the weight of said sound-producing device or a portion thereof upon one of its suspending-cords, said draft-receiving means comprising means whereby the force obtained thereby may be multiplied and transformed to operate said lever, and a spring for holding said striker 100 and its actuating parts in position to be operated upon as aforesaid.

13. In an apparatus of the character specified for producing sound-vibrations in water, a sound-producing device comprising a resonant body, a striker for sounding the same, a lever, a latch joined to said lever and adapted to engage with a portion of said striker so raising said striker to a striking position with an automatic release when the lever is moved 105 in one direction, and which latch is adapted to assume a position to engage said striker as aforesaid when said lever is moved in another direction, and means for actuating said lever. 110

14. In an apparatus for producing sound-vibrations in water, the combination with two suspension-cords of a sound-producing device hanging pendent therefrom, the same comprising a resonant body, a striker for sounding the same, a lever connected to engage with said striker whereby it may be raised to a striking position with an instantaneous release, and one or more pulleys connecting with said lever around which pulley or pulleys one of said suspending-cords is 120 adapted to be passed, substantially as and for the purposes set forth. 115

15. In an apparatus for producing sound-vibrations in water, the combination with two suspension-cords of a sound-producing 130

device hanging pendent therefrom, the same comprising a resonant body, a striker pivotally hung by its arm within said resonant body for sounding the same, said arm of the striker being slotted at the point of its pivotal connection, a stop for said arm of the striker beyond the point of its said pivotal connection, a spring connected with the striker between said stop and said pivotal connection, and means for operating said striker by the transfer of the weight of said device or a portion thereof from one suspending-cord to the other.

16. In an apparatus for producing sound-vibrations in water, the combination with two suspension-cords of a sound-producing device hanging pendent therefrom, the same comprising a resonant body, a striker pivotally hung by its arm within said resonant body, a spring connecting at one end with said arm of the striker beyond the point of its pivotal connection, and at its other end with one arm of a lever, said lever, a pivoted-latch secured to the other arm thereof and adapted to engage with an inclined surface of said striker, stop-surfaces for defining the position of said latch and means whereby said lever may be operated by the transfer of the weight of said sound-producing device, or a

portion thereof from one suspending-cord to the other.

17. In an apparatus for producing sound-vibrations in water, a casing or shell forming an internal or resonating chamber, and a sound-bow or resonating member at the open mouth of said casing, which sound-bow has a mean diameter considerably less than the mean diameter of said casing taken between the sides thereof.

18. In an apparatus for producing sound-vibrations in water, a casing or shell forming an internal or resonating chamber and a sound-bow or resonating member at the open mouth of said casing, which sound-bow projects inwardly from said mouth of the casing to which it is secured, and so far that its mean diameter will be less than the mean diameter of said casing taken between the sides thereof, whereby said sound-bow will close to an appreciable degree the mouth of the casing and assist in forming or inclosing the said internal or resonating chamber.
